CHUTE CONSTRUCTION

Filed May 31, 1930

FIG. 1

INVENTOR.
KENNETH F. TRIGGS.

BY

Lockwood Lockwood Goldsmith & Salt

ATTORNEYS.

UNITED STATES PATENT OFFICE

KENNETH F. TRIGGS, OF HUNTINGTON, INDIANA, ASSIGNOR TO THE MAJESTIC COMPANY, OF HUNTINGTON, INDIANA, A CORPORATION

CHUTE CONSTRUCTION

Application filed May 31, 1930. Serial No. 458,396.

This invention relates to a coal chute construction and one wherein certain simplifications have been obtained.

The chief object of the invention is to simplify the construction of a coal chute device, whereby the same may readily be applied to structures that have been built and in which an opening has been made for the mounting of the chute therein.

10 One feature of the invention consists in the adjustable peripherally enveloping clamping arrangement provided and the self cleaning or non-interfering character thereof.

15 The full nature of the invention will be fully understood from the accompanying drawings and the following description and claims.

In the drawings Fig. 1 is a perspective view of a coal chute construction with the closure opened.

20 Fig. 2 is a transverse sectional view taken on line 2—2 of Fig. 1 and in the direction of the arrows.

25 In the drawings 10 indicates a tubular construction, preferably rectangular in form and of a length that is sufficient to accommodate substantially all thicknesses of walls or foundations. Secured to the forward edge 30 of said tubular member is a face plate 11 having an opening 12 therein. The face plate includes the ears 13 upon which is pivotally supported a closure 14, which preferably has a latch construction indicated generally at

35 16 on its inner face. The chute may, if desired, be provided with an inclined extension 17 having the stops 18 and the linkage support 19 therefor. The tubular member upon two opposite sides includes a plurality of 40 substantially semi-circular openings 20, the same being punched therefrom, and the surplus metal being turned back as at 21 to form a double reinforced and curved edge 22.

45 Telescopically mounted upon the opposite or inner end of the tubular member is a clamping member, herein shown in the form of a welded angle iron having the base portion 23 and the outwardly projecting flange portions 24. Flange 24 is apertured as at 25 50 in substantially horizontal alignment with

the opening 20. A hook-bolt 26 having the hook portion 27, is seatable in opening 20 and engages the double reinforced edge thereof and extends rearwardly with the threaded end 28 passing through opening 25. An 55 anchoring nut 29 draws the frame against the exterior face 30 of the foundation or wall, having the openings 31 therein, and draws the telescopic member 23—24 into clamping engagement with the inner face of 60 the wall 32.

By means of the aforesaid construction, it will be observed that a relatively light sheet metal tubular chute can be provided and that the strain is taken by a reinforced portion and that the anchoring means are self clearing, in that the chute exposed portions of the hook-bolts are directed rearwardly. The face plate 11 and the peripherally enveloping telescopic clamping member 24, clamping 70 and rigidly mount the entire chute construction in the opening 31 of the wall or foundation. The telescopic member may be reversely positioned, that is with the base portion 23 oppositely directed, or a different 75 form of clamping member may be substituted.

The invention claimed is:—

1. A coal chute construction including an exterior exposed wall engaging opening defining frame having an opening therein, a closure for said opening, a tubular construction extending rearwardly from the frame and positioned in the wall opening, a wall clamping member peripherally enveloping 85 and slidably mounted on the tubular construction and bearing upon the wall adjacent the opening therein, said tubular portion construction including a perforation in a plurality of sides, and a hook-bolt for each perforation and having the hook portion seatable therein and the other end adjustably associated with the wall clamping member.

2. A coal chute construction including an exterior exposed wall engaging opening defining frame having an opening therein, a closure for said opening, a tubular construction extending rearwardly from the frame and positioned in the wall opening, a wall clamping member peripherally enveloping 95 100

and slidably mounted on the tubular construction and bearing upon the wall adjacent the opening therein, said tubular portion construction including a perforation in a plurality of sides, and a hook-bolt for each perforation and having the hook portion seatable therein and the other end adjustably associated with the wall clamping member, the main portion of the hook-bolt being positioned without the tubular construction and the hook portion thereof being positioned within the tubular construction and rearwardly directed providing a minimum of interference in the chute.

3. A coal chute construction including an exterior exposed wall engaging opening defining frame having an opening therein, a closure for said opening, a tubular construction extending rearwardly from the frame and positioned in the wall opening, a wall clamping member peripherally enveloping and slidably mounted on the tubular construction and bearing upon the wall adjacent the opening therein, said tubular portion construction including a perforation in a plurality of sides, and a hook-bolt for each perforation and having the hook portion seatable therein and the other end adjustably associated with the wall clamping member, the main portion of the hook-bolt being positioned without the tubular construction and the hook portion thereof being positioned within the tubular construction and rearwardly directed providing a minimum of interference in the chute, the perforations in said tubular construction being formed by piercing the same and turning rearwardly the pierced portion of the metal for forming a reinforced bearing for the curved portion of the hook-bolt.

40 In witness whereof, I have hereunto affixed my signature.

KENNETH F. TRIGGS.
